CLAIM

The ornamental design for a guard for use with a power tool, as shown and described.

DESCRIPTION

FIG. 1 is a perspective view of a guard for use with a power tool showing our new design;

FIG. 2 is a rear elevation view thereof;

FIG. 3 is a right-side elevation view thereof;

FIG. 4 is a front elevation view thereof;

FIG. 5 is a left-side elevation view thereof;

FIG. 6 is a top plan view thereof with the latch of the guard in a closed position;

FIG. 7 is a bottom plan view thereof;

FIG. 8 is top plan view thereof with the latch of the guard in an opened position;

FIG. 9 is a side isometric view thereof coupled to an exemplary power tool;

FIG. 10 is a front isometric view thereof coupled to an exemplary power tool; and,

FIG. 11 is a bottom plan view thereof coupled to an exemplary power tool.

The broken lines in the drawings illustrate portions of the guard and an exemplary power tool that do not form part of the claimed design.

The dashed lines form no part of the claimed design.
